UNITED STATES PATENT OFFICE.

FRANCIS J. LAPOINTE, OF ANN ARBOR, MICHIGAN.

OIL BURNER.

Application filed July 27, 1928. Serial No. 125,134.

This invention relates to oil burners and has for its object the production of a device of this character which will be absolutely noiseless and free from soot.

5 This object is attained by the mechanism illustrated in the accompanying drawings.

For the purpose of illustrating the invention, one preferred form thereof is illustrated in the drawings, this form having 10 been found to give satisfactory and reliable results, although it is to be understood that the various instrumentalities of which the invention consists can be variously arranged and organized, and the invention is not limited to the precise arrangement and organization 15 of these instrumentalities as herein shown and described except as required by the scope of the appended claims.

Of the drawings:

20 Figure 1 represents a plan of an apparatus embodying the principles of the present invention.

Figure 2 represents a vertical section of the burner on line 2, 2, on Fig. 1.

25 Figure 3 represents a vertical section of same on line 3, 3, on Fig. 1, the burner casing being shown in elevation.

Figure 4 represents a plan of the gas generator of the burner.

30 Figure 5 represents a horizontal section of the burner on line 5, 5, on Fig. 2 with the cylindrical perforated plates or shells removed.

Figure 6 represents a vertical section of the lower end of the generator, showing the 35 carbon remover.

Figure 7 represents a vertical section of the oil valve and mechanism for actuating the carbon remover.

40 Figure 8 represents a section of the pipe leading to the chimney from the heater in which the oil burner is installed.

Figure 9 represents a horizontal section on line 9, 9, on Fig. 8, and

45 Figure 10 represents a plan of the central portion of the burner plate and showing the ears to which the vapor generator is secured.

50 Similar characters indicate like parts throughout the several figures of the drawings.

In the drawings, 10 is a tubular member

or conduit with its forward end 11 open for the admission of air thereto. The rear end of this member 10 is provided on its upper face with an annular flange 12 on which is supported a metal cylinder 13 having a ring 14 supported on its upper end.

Within the flange 12 the upper face of the member 10 has an opening 15 therethrough communicating with an air chamber 16.

The member 10 has projecting upwardly within the air chamber 16 a plurality of bosses 17 on which is supported a plate 18.

Centrally disposed in the plate 18 and extending upwardly therefrom is a generator 19, the upper end of which is provided with a cover 20.

Within the generator 19 is an oil well 21 which extends downwardly below the plate 18 and has extending laterally from its lower end a pipe 22, the outer end of which is connected to a valve casing 23.

This valve casing 23 has connected thereto a pipe 24 leading to an oil level controller 25 which may be of any well known construction and therefore is not illustrated in detail.

The oil level controller is connected by a pipe 26 to a safety device 27, said safety device having a pipe 28 leading thereto from the tank containing the supply of oil to be used.

The safety device 27 is of well known construction, being the Remnsnider oil control 85 and safety trip valve. As there is no invention in this particular element of the invention it is deemed unnecessary to illustrate the same in detail.

Within the casing 23 is a valve 29 threaded to the casing at 30 and rotatable about its axis by means of the hand wheel 31 secured to the valve stem 32.

Surrounding the valve casing 23 is secured a collar 33 which has an arm 34 extending 95 forwardly therefrom and provided with an index finger 35 adapted to coact with a scale on the front face of the wheel 31 to determine the proper position of the valve 29.

When the valve 29 is opened as shown in 100 Fig. 7 of the drawings the oil from the supply tank will pass through the pipe 28, the

safety device 27, the oil level controller 25, to the interior of the valve casing 23, and then through the pipe 22 to the oil well 21.

Extending upwardly from the bottom of 5 the oil well 21 and centrally disposed therein is a stud 36 having a gear 37 freely revoluble thereon.

This gear 37 meshes with and is supported by a pinion 38 secured to a shaft 39 mounted 10 in a bearing 40 within the oil pipe 22.

The opposite end of the shaft 39 has a flat sided slot 41 formed therein into which the flat sided extension 42 of the valve 29 is disposed.

15 As the valve 29 is rotated causing it to move endwise the extension 42 will move endwise in the flat sided slot 41 of the shaft 39.

A sleeve 43 surrounds the coacting ends of 20 the shaft 39 and extension 42.

Secured to and revoluble with the gear 37 is a cylinder 44 extending to the top of the oil well, this cylinder having oppositely disposed openings 45 extending through the 25 wall thereof and the upper end of said cylinder flares outwardly and is slotted as indicated at 46.

Every time the valve 29 is adjusted to 30 vary the admission of oil to the oil well 21, this cylinder 44 will rotate with the gear 37 and loosen any sediment which may remain in the oil well 21.

In the generator 19 and on opposite sides 35 of the oil well 21 are gas passages 47 which communicate at their upper end with the upper end of the oil well and at their lower ends with two radiating passages 48 in the plate 18, the outer ends of these radiating passages being closed by threaded plugs 49.

40 The upper face of the plate 18 is provided with a plurality of concentric grooves 50 communicating with the passages 48.

Upon opposite sides of the grooves 50 and 45 extending upwardly from the plate 18 are a plurality of perforated annular plates 51.

Each pair of plates 51 forms a vapor or 50 gas passage extending upwardly within the cylinder 13 and between the various pairs of perforated plates 51 are air spaces 52 closed at the top by weighted covers 53 loosely 55 mounted upon the upper ends of the plates 51.

The lower ends of the air spaces 52 communicate by means of openings 54 in the plate 18 with the air chamber 16 beneath said plate.

When the burner is in operation the atmospheric air passes through the open end 11 into the tube or conduit 10 through the 60 air chamber 16 and the openings 54 into the air spaces 52, and then through the perforated plates 51 to supply sufficient air for combustion when the vapor or gas admitted to the grooves 50 is ignited.

The generator 19 has oppositely disposed 65 ears 55 which are secured by bolts 56 to inwardly extending ears 57 projecting into the central opening 58 in the plate 18.

The wall surrounding the oil well 21 is comparatively thin as shown at 59 in order 70 that the heat generated in the burner may readily pass through said wall to act upon the oil contained within the well.

Normally the oil within the well is at a level indicated by dotted lines at 60 on Fig. 75 2 of the drawings.

When the burner is in operation the heat transmitted through these walls will cause the oil within the well 21 to boil and form a vapor, this vapor rising to the top of the 80 generator beneath the cover 20 and passing through the passages 47 into the radiating passages 48 which communicate with all of the burning grooves 50.

When the vapor in these grooves is ignited 85 it passes upwardly between the various pairs of perforated plates 51 and forms a blue flame free from all soot and sediment.

This combustion of the vapor generated from the boiling oil causes a suction which 90 draws through the perforations in the plates 51 sufficient air from the air chamber 16 and tube 10 required for the proper combustion of the vapor.

The amount of flame coming from the 95 burner through the ring 14 may be regulated by means of the valve 29.

In addition to the radiating passages 48 are other radiating passages 61 which also communicate with all of the burning 100 grooves 50.

The inner end of these radiating passages 61 are in communication with a semi-annular pipe 62 from which extends a pipe 63 through the tube 10 to any main supply of 105 gas, such as the city gas main.

This pipe 63 has a valve 64 therein by which the supply of city gas to the burner may be controlled or completely shut off. Where the city gas is not available a supply 110 of gasoline or similar material may be admitted to the burner through the pipe 63 when it is desired to place the burner in operation.

The gas admitted to the grooves 50 115 through the pipe 63 is for the purpose of starting the burner to place it in proper condition where it will vaporize the oil admitted to the well 21.

Usually this gas is admitted through the 120 pipe 63 and ignited for a period of practically twenty minutes, and at the end of this period all of the burner is in such heated condition and transmitting its heat to the oil in the well 21 that the oil will boil and 125 become vaporized.

None of the oil in the well will pass through the passages 47 to the slots 50 in the

plate 18, and therefore these slots and the entire plate will always be absolutely free from carbon and any other foreign substances. In other words, the slots 50 and 5 burner plate 18 will be perfectly clean at all times as only a gas or vapor is burned therein.

As soon as the burner is sufficiently heated to vaporize the oil the valve 64 is shut off 10 and no more city gas is required.

It is obvious also that no pilot is required because as soon as the oil begins to vaporize it will continue to furnish a blue flame until the supply of oil to the well 21 is shut off by 15 means of the valve 29.

Should for any cause the oil be admitted to the well 21 when the burner was not in operation, then the oil thus admitted to the well would overflow into the grooves 50 20 through the perforations in the plates 51 and pass through the air chamber 16 into the rear end of the tube or conduit 10.

To take care of any such overflow of oil the bottom of the rear end of the tube 10 is 25 inclined downwardly as shown at 65.

From the front end of the downwardly inclined bottom 65 is an overflow pipe 66 which is connected by means of a pipe 67 to the safety bucket 68 forming part of the 30 safety device 27.

This connecting pipe 67 also communicates with a small pipe 69 extending from the oil level controller 25.

This pipe 69 is provided in case there 35 should be any excess of oil in the oil level controller and provides a means for taking off such excess oil.

On one side of the tube 10 is a bracket 70 which is adjustable vertically relative to 40 the tube 10 and this bracket 70 carries the oil level controller 25.

The adjustment of the bracket 70 is provided so that the oil level controller 25 may be raised or lowered thereby varying the 45 level of the oil in the well 21 as desired.

The rear end of the tube or conduit is supported by a leg 71, and the front end is supported by legs 71^x.

The burner is installed in the fire pot of 50 any ordinary heater with the open end of the air conduit extending outwardly through the ash door opening.

As no oil is burned in the burner there is no need of a connection with a chimney and 55 consequently the damper 72 in the pipe 73 is kept closed at all times.

The pipe 73 connects with a T-pipe 74 having a partition 75 therein and a downwardly extending branch 76 open at the 60 lower end.

Any gas or vapor escaping from the fire pot around the damper 72 will strike against the partition 75 and be deflected downwardly and then upwardly to the chimney flue 65 through the pipe 77.

This partition 75 prevents any down draft in the chimney from passing by the damper 72 and blowing out the flame of the burner as such down draft will be deflected downwardly by the partition and then discharged 70 into the cellar from the lower end of the branch pipe 76.

It is to be noted that neither pressure tanks, electric fans, nor motors are required to operate the burner and that the generator 75 operates entirely without pressure. The consequence is that when the burner is in use it is absolutely noiseless.

By means of the controller 25 a fixed level of oil is maintained in the generator 21 and 80 as this oil gets hot, it boils and throws off a vapor or gas.

It is this vapor which is burned, the oil itself never being burned as it is confined in the well 21 closed at the top by the cover 20. 85

When the vapor has been generated from the boiling oil it travels through the vertical passages 47 to the radiating passages 48 and the burning grooves 50.

When this vapor reaches the burning 90 grooves 50, it rises between the perforated plates 51, picking up air admitted through the perforations in said plates, the vapor burning as it rises.

The faster the oil is fed to the well 21, 95 the more vapor will be thrown off as the oil boils, and as a consequence the burner gets hotter and hotter.

Either kerosene, gasoline, or crude fuel oil distillate may be used in the burner and 100 as the gas alone is burned, and not the oil, the entire burner is free from carbon even in the generator.

What little carbon may accumulate in the generator after long use does not in any 105 manner interfere with the operation of the burner and is of a soft nature and not a hard carbon which would be liable to cause a blockage in the generator.

The carbon is soft because it is saturated 110 with oil in the well 21 and is easily stirred by the rotation of the cylinder 44 within said well.

In lighting the burner, it can be lit with ordinary city gas by simply using a wax 115 taper, or match, and dropping it into the burning grooves and turning on the gas.

After the gas has been burning for fifteen or twenty minutes, the bottom plate 18 and plates 51 will be heated so hot that the generator will have accumulated sufficient heat to start generating its own gas or vapor.

As soon as the generator produces its own vapor and this is fed to the grooves 50 in the burner plate 18, the supply of city 125 gas will be shut off entirely.

In the absence of city gas, other means may be used for lighting the burner as for instance placing an asbestos wick or torch saturated with gasoline in one of the burn- 130

ing grooves and supplying this wick with gasolene until the burner is sufficiently hot.

This gasolene may be in an oil cup or other receptacle connected at the bottom to 5 the gas pipe through which the gasolene is fed to the wick and the cup is adjusted so that the gasolene will be fed as fast as required to keep it burning.

By the time the cup is empty the burner 10 has become sufficiently heated to cause it to generate its own gas and thereafter the vapor generated will continue to burn and no more gasolene will be required.

It is believed that the operation and many 15 advantages of the invention will be understood without further description.

Having thus described my invention, I claim:

1. The combination of a plate provided 20 with a plurality of concentric grooves in its upper face and radiating passages connecting said grooves; a pipe leading from a main gas supply to one of said radiating passages; a vapor generator centrally disposed on said plate and adapted to deliver the vapor generated to another radiating passage; a valve in said pipe; perforated plates extending upwardly from the opposite sides of said grooves and forming an 25 annular chambers; and means for supplying air to said chambers.

2. The combination of a plate provided with a plurality of grooves in its upper face; a member supported by and extending upwardly above said plate provided with a 30 well communicating at the top with passages leading downwardly; means for admitting oil to said well; means for vaporizing said oil in said well; and radial passages communicating with the lower ends of said downwardly leading passages and through which the vapor generated in said well may be delivered to said grooves.

3. The combination of a plate provided 45 with a plurality of concentric grooves in its upper face; a member centrally disposed on said plate and extending upwardly therefrom, said member having a well therein communicating at the top with passages leading downwardly to said grooves; means for admitting oil to said well; means for vaporizing said oil in said well; and means whereby the vapor generated may be delivered to said grooves from the lower ends 50 of said downwardly leading passages.

4. The combination of a plate provided with a plurality of grooves in its upper face; perforated walls extending upwardly on opposite sides of said grooves; means 60 for admitting air above said grooves through said walls; a well adjacent said grooves and extending above said plate; means for admitting oil to said well; means for vaporizing said oil in said well; means 65 whereby the vapor generated may be de-

livered from the upper end of the well to said grooves; and means for carrying away any oil overflowing from said well.

5. The combination of a plate provided with a plurality of grooves in its upper face 70 open at the top; an air chamber beneath said plate having a tubular extension open at the outer end and through which air is admitted to the chamber, said plate having openings therethrough between said grooves 75 for the passage of air; and means for vaporizing oil at a point above said plate and delivering the vapor generated to said grooves through a plurality of passages communicating with the upper end of said vaporizing means.

6. The combination of a plate provided with a plurality of open grooves in its upper face; perforated plates extending upwardly from the opposite sides of said grooves; a 85 casing opened at one end and provided at its other end with an air chamber beneath said plate, said plate having openings therethrough between said grooves for the passage of air; and means for vaporizing oil 90 at a point above said plate; and means delivering the vapor generated to said grooves through vertical passages the upper ends of which communicate with the upper end 95 of said vaporizing means.

7. The combination of a plate provided with a plurality of grooves in its upper face; perforated plates extending upwardly from the opposite sides of said grooves; covers supported by said perforated plates for the 100 air spaces between said plates; an air chamber beneath said plate, said plate having openings therethrough between said grooves for the passage of air to said air spaces; means for vaporizing oil and delivering it to 105 said grooves; and independent means for delivering to said grooves gas from a main supply.

8. The combination of a plate provided with a plurality of grooves in its upper face; an air chamber beneath said plate, said plate having openings therethrough between said grooves for the passage of air; means for delivering gas to said grooves from a main source of supply; and independent means 115 for vaporizing oil and delivering the vapor generated to said grooves.

9. The combination of a plate provided with a plurality of concentric grooves in its upper face and radiating passages connecting said grooves; a pipe leading from a main gas supply to one of said radiating passages; a vapor generator centrally disposed on said plate provided with an oil well and passages extending from the top of said well and adapted to deliver the vapor generated to another radiating passage; a valve in said pipe; perforated plates extending upwardly from the opposite sides of said grooves and forming annular chambers 120 125 130

and means for supplying air to said chambers.

10. The combination of a plate provided with a plurality of grooves in its upper face; a well adjacent said grooves; means for admitting oil to said well; means for vaporizing said oil; means whereby the vapor generated may be delivered to said grooves; and a member within said well adapted to 10 be rotated, said member extending upwardly above the oil level.

11. The combination of a plate provided with a plurality of concentric grooves in its upper face; a well centrally disposed on 15 said plate and extending upwardly therefrom; means for admitting oil to said well; means for vaporizing said oil; means whereby the vapor generated may be delivered to said grooves; and a cylindrical member 20 within said well extending above the oil level and adapted to be rotated.

12. The combination of a plate provided with a plurality of grooves in its upper face; a well adjacent said grooves; means 25 for admitting oil to said well; means for vaporizing said oil; means whereby the vapor generated may be delivered to said grooves; a valve for controlling the flow of oil to said well; and a hollow cylinder with- 30 in and extending lengthwise of said well and adapted to be moved about its axis whenever said valve is actuated.

13. The combination of a plate provided with a plurality of grooves in its upper 35 face; a well adjacent said grooves; an oil pipe leading to said well; a valve for controlling the flow of oil through said pipe; a stud within said well; a gear freely rotatable about said stud; a hollow cylinder sup- 40 ported by and rotatable with said gear; a pinion meshing with said gear; means connected with said valve for rotating said pinion; and means for vaporizing oil in said well and delivering the generated vapor to 45 said grooves.

14. The combination of a plate provided with a plurality of grooves in its upper face; a well adjacent said grooves; means for vaporizing oil in said well and delivering 50 the generated vapor to said grooves; an oil supply pipe leading to the bottom of said well; a hollow cylinder extending lengthwise of said well and having side openings therein; a valve in said supply pipe; and 55 means extending through said pipe and actuated by said valve for rotating said cylinder.

15. The combination of a cylindrical cas- 60 ing open at the top, a plate disposed with- 65 in and near the bottom thereof provided with a plurality of grooves in its upper face; perforated plates extending upwardly from the opposite sides of said grooves; covers supported by said perforated plates 70 for the air spaces between said plates; an

air chamber within said casing beneath said plate, said plate having openings there- 75 through between said grooves for the pas- sage of air; and means for vaporizing oil and delivering the generated vapor to said 80 grooves.

16. The combination of a cylindrical cas- 75 ing open at the top; a plate disposed within and near the bottom thereof provided with a plurality of grooves in its upper face; an 80 air chamber within said casing beneath said plate, said plate having openings there- through between said grooves for the pas- 85 sage of air; an air conduit leading to said air chamber; and a pipe extending through said conduit for delivering gas to said 90 grooves from a main source of supply.

17. The combination of a cylindrical cas- 85 ing open at the top; a plate disposed within and near the bottom thereof provided with a plurality of concentric grooves in its up- 90 per face and two sets of radiating passag- 95 es connecting said grooves; a pipe leading from a main gas supply to one set of radiating passag- 100 es; a vapor generator centrally dis- posed on said plate and adapted to deliver the vapor generated to the other set of radiating passag- 105 es; a valve in said pipe; per- 110forated plates extending upwardly from the opposite sides of said grooves and forming annular chambers; and a conduit leading to the bottom of said casing for supplying air to said chambers.

18. The combination of a cylindrical cas- 100 ing open at the top; a plate disposed within and near the bottom thereof provided with a plurality of grooves in its upper face; a member supported by said plate provided with a well connected at the top by passag- 105 es leading to said grooves; means for admit- 110ting oil to said well; means for vaporizing said oil in said well; means whereby the vapor generated may be delivered to said grooves; and an air conduit communicating with the bottom of said casing.

19. The combination of a plate provided with a plurality of concentric grooves in its upper face; a member centrally disposed on said plate and extending upwardly there- 115 from, said member having a well therein connected at the top by passag- 120 es leading to said grooves; means for admitting oil to said well; means for vaporizing said oil in said well; means whereby the vapor gen- 125 erated may be delivered to said grooves; a device for controlling the level of the oil in said well; a safety device including a bucket; and a pipe leading from said controlling means to said bucket.

20. The combination of a generator for 125 vaporizing oil including a centrally disposed oil well; automatic means for maintaining a constant level of the oil within said well; means surrounding said well including a plu- 130 rality of concentrically disposed burning

grooves and passages leading from said burning grooves to the top of said generator and through which the vapor generated in said well may pass therefrom to said 5 grooves; and means for providing a continuous supply of air to confined spaces above said burning grooves.

21. The combination of a plate provided with a plurality of open burning grooves 10 in its upper face; an oil well adjacent and extending above said grooves; means for maintaining in said well a constant supply of oil at a level above said plate; means for vaporizing the oil in said well; means whereby 15 the vapor generated may be delivered from the upper end of said well through downwardly extending passages to said burning grooves; and means for providing a continuous supply of air to confined spaces 20 above said burning grooves.

22. The combination of a plate provided with a plurality of concentric open grooves in its upper face; a well centrally disposed on said plate and extending upwardly therefrom above said grooves; means for maintaining oil in said well at a constant level above said plate; means for vaporizing said oil; and means whereby the vapor generated may be delivered from the upper end of said 25 well to said grooves, through a plurality of vertical passages communicating at the upper end with said well and at the lower end with said grooves.

23. The combination of a plate provided 30 with a plurality of open grooves in its upper face; perforated walls extending upwardly from the opposite sides of said grooves; means for admitting air above said grooves through said walls; a well adjacent 35 and extending above said grooves; means for maintaining oil in said well at a constant level above said plate; means for vaporizing said oil; and means whereby the vapor generated may be delivered from the upper end 40 of said well to said grooves through passages external to said well.

24. The combination of a plate provided 45 with a plurality of open grooves in its upper face; an oil well extending upwardly above said plate; perforated plates extending upwardly from the opposite sides of said grooves; removable annular covers supported by said perforated plates and closing the upper ends of the air spaces between

said plates; an air chamber beneath said plate, said plate having openings therethrough between said grooves for the passage of air; means for maintaining oil in said well at a constant level above said plate; and means for vaporizing oil in said well; and means for delivering the vapor generated from the upper end of the well to said grooves.

25. The combination of a plate provided with a plurality of open grooves in its upper face; an oil well extending upwardly above said plate; means for maintaining a constant supply of oil in said well at a level above said plate; an air chamber beneath said plate, said plate having openings therethrough between said grooves for the passage of air; means for vaporizing oil in said well and delivering the vapor generated from the upper end of said well to said grooves; and means for temporarily delivering a priming gas to said grooves from a main source of supply.

26. The combination of a plate provided with a plurality of grooves in its upper face; an oil well extending upwardly from said plate and in which the oil is adapted to be vaporized; means for maintaining a constant supply of oil in said well at a level above said plate; means whereby the vapor generated may be delivered from the upper end of said well to said grooves; a safety device externally disposed relatively to said oil well and plate; an oil level controller; means whereby the oil will be delivered through said safety device and controller to said well; and a valve between said controller and well.

27. The combination of a plate provided with a plurality of grooves in its upper face; means for vaporizing oil and delivering the vapor generated to said grooves including an oil well from the upper end of which the vapor generated is discharged; a controller for maintaining the oil in said well at a constant level above said plate; a valve between said controller and well; a safety device including a bucket through which the oil passes to said controller; and means whereby any overflow of oil from said well will be discharged into said bucket.

Signed by me at Ann Arbor, Michigan this 23 day of July 1926:

FRANCIS J. LAPOINTE.
